(57) CLAIM

The ornamental design for a paint bucket with brush wiping lip and finger grip, as shown and described.

DESCRIPTION

FIG. 1 is a top and side perspective view of a paint bucket with brush wiping lip and finger grip, showing my new design;

FIG. 2 is a side view thereof, the unshown opposite side being of mirror image appearance;

FIG. 3 is a top view thereof;

FIG. 4 is a bottom view thereof; and,

FIG. 5 is a sectional view taken in the direction of the arrows upon the line 5—5 of FIG. 3.
